RECEPTACLE AND CLOSURE MEANS
THEREFOR

Sidney J. Rudolph, Pittsburgh, Pa.

Application May 10, 1943, Serial No. 486,420

8 Claims. (Cl. 222—559)

My invention relates to a closure means for closing orifices, slots or similar openings of rigid or collapsible receptacles; but more particularly relates to a receptacle comprising a closure means composed of parts which are joined to the receptacle, the closure means comprising one part, hereinafter referred to as a cap-seat, which has an opening therethrough through which the contents for or of the receptacle can pass, and another part, hereinafter referred to as a cap, which is movable along the cap-seat to a position closing or covering the opening to tightly seal it, or to positions partially closing or covering the opening to control the rate of passage of the contents of the receptacle, or to a position fully exposing the opening. Preferably, the parts are so related that the cap tightly engages the cap-seat in fully or partially closed position and is comparatively loose on the cap-seat in open position; the cap, however, being interlocked with the cap-seat in all its positions so that it will not separate from the receptacle proper.

It is an object of my invention to provide a closure means having a closing cap, restrictably movable to and between opening-covering and opening-uncovering positions by simple rectilinear movements which can be executed manually, the cap tending to remain in the position in which it is set.

It is an important object of my invention to provide a receptacle, preferably a glass receptacle, having a cap-seat through which a dispensing or discharge-opening passes, and a cap, slideable on the cap-seat for tightly and leaklessly closing the discharge-opening or for partially closing the discharge-opening while firmly seated on the cap-seat, for controlling the discharge-rate of the contents of the receptacle.

In accordance with certain preferred forms of my invention, the cap and cap-seat are so formed as to cause the parts to be pressed or forced together when the cap is in a position fully or partially closing the discharge-opening, the pressure on the contacting surfaces of the cap and cap-seat being substantially uniformly distributed thereover for a sufficient area to keep the cap in relatively fixed position on the cap-seat whenever the cap is placed for fully or partially closing the discharge-opening. In closed position the contacting areas are sufficiently large about the discharge-opening to insure a tight closure by abutting relation of such areas. To this end the general shape or form of the abutting surfaces of the cap and cap-seat correspond so that they fit or mate in the fully and the partially closing po-

sitions of the cap. The cap and cap-seat are provided with interlocking means which enable the cap to slide easily along the cap-seat from open position where it is comparatively loose on the cap-seat, to closing positions, firmly engaging the cap-seat in any such closing position; the interlocking means also causing the pressure-force on the cap to act in directions which produce no tendency to move the cap away from any closing position in which it was placed, so that the cap will remain put until moved by some externally applied force.

It is a further object of my invention to provide a receptacle having a closure means of the type described, which can be economically and readily produced in quantity by high-speed production machinery, with a minimum use of material.

It is an additional object of my invention to provide a closure means of the type described, comprising a cap and a cap-seat which do not require accurate dimensional relations for cooperation.

Other objects and features of my invention in addition to those aforesaid can be gathered from the following description thereof, which is to be taken in conjunction with the accompanying drawing in which similar reference numerals refer to similar parts. In the drawing:

Fig. I is a perspective view of a small-sized collapsible tube embodying my invention;

Fig. II is a sectional view taken substantially along the line II—II of Fig. I, especially showing the cap and cap-seat in longitudinal or lengthwise section;

Fig. III is an elevational view of the closure means of Fig. I, but with the cap in opening-uncovering position;

Figs. IV and V are sectional views taken along the lines IV—IV and V—V, respectively, of Fig. I, these lines being transverse to the line II—II;

Fig. VI is a view similar to that of Fig. III, of a modified form of my invention, but with the cap omitted for clarity;

Fig. VII is a part perspective view of a glass flask having a closure means embodying my invention;

Fig. VIII is a partial vertical sectional view of another modification, with the cap omitted; and

Figs. IX and X are sectional views substantially on the lines IX—IX and X—X, respectively, of Fig. VIII, with the cap added.

For the purpose of describing preferred forms of my invention, I have shown in Fig. I a metallic collapsible tube 2 for pasty substances and

the like, and in Fig. VII a glass container or flask 4, for liquids, as representative of receptacles embodying my invention. Each of the receptacles 2 and 4 comprises a top-wall which has formed therewith, or secured thereto, a cap-seat; the discharge-opening for the receptacle passing through the top-wall and cap-seat. A cap slides along the cap-seat controls the discharge-opening.

In the drawing a cap-seat 6 is shown as having such a discharge-opening 8 passing through it and through a top-wall 10 of the tube 2, or a top-wall 12 of the flask 4. The cap-seat 6 comprises an extended body-portion 16 substantially T-shaped in cross-section, having a relatively wide leg member 18 projecting upward from the associated top-wall, and a top cross member 20 extending the length of the body-portion and extending slightly beyond the sides of the leg 18 to provide a flange 22 on each side thereof. The flanges 22 are substantially parallel and alike, being spaced slightly from the outer surface of the top-wall 10 or 12, to provide a somewhat narrow cap-seat channel 24 below each flange 22, on the outer sides of the leg 18.

The discharge-opening 8 passes through the upright leg 18, near an end of the body-portion 16, but not so close as to prevent proper closing of the discharge-opening. For a receptacle such as the tube 2 it is preferable to locate the discharge-opening at about the center of the top-wall 10; while for a receptacle such as the flask 4 it may be located close to the narrow edge of the long and narrow top-wall 12. For controlling the discharge-opening a cap 26 is provided for the tube 2 and a structurally similar cap 26' for the flask 4.

The cap 26 comprises spaced side-walls 28 bridged by an integral top bridging member 30 across the tops of the side-walls 28, the bridging member being transversely ridged or otherwise roughened on its top surface to facilitate gripping. The bottom edge of each side-wall 28 is directed inwardly to provide a runner or flange 32 which can be continuous or in the form of spaced lugs. The flanges 32 are spaced from the bottom surface of the bridging member 30 to provide an extended cap-channel on the inner side of each side-wall 28. Each channel on the cap extends for the full length of the cap, is of uniform width along its length, and is adapted to receive a flange 22. The flanges 32 are received in the cap-seat channels 24. Consequently the cap and cap-seat flanges and channels are interlocking means which prevents the cap from being lifted from the cap-seat. However, the flanges are relatively slideable in their respective channels so that the cap can be slid lengthwise between a closed position fully closing the discharge-opening, as shown in Fig. I, and an open position exposing the discharge-opening, as shown in Fig. III.

The cap may be prevented from moving much beyond its closing and opening positions by stops 34 and 36 suitably located at the ends of the channels 24. Preferably the stop or abutment nearest the discharge-opening is somewhat accurately positioned so that the cap will be stopped in satisfactory fully closing position with the discharge-opening substantially centrally beneath the cap; while the other stop or abutment is located a distance from the first which will permit the cap to move a distance slightly more than twice its length, although this distance may

be more or less and may be made dependent upon the location of the discharge-opening.

For a collapsible tube including the closure means described, the body-portion 16 may be formed with the rest of the top-wall 10, the channels 24 being die-formed in the body-portion. One of the stops or abutments 34 or 36 may be formed at this stage also, the other being formed later by peening, swaging, crushing or other upsetting operation after the cap has been slid in place if the cap side-walls cannot spread. In the embodiment shown in Fig. I, the extreme ends of the flanges 22 are forced into the channels 24 to provide the stops 36, the stops 34 comprising an upright wall-portion integral with the end of the body-portion.

As shown more particularly in Figs. III and VI, each flange 22 has a transversely enlarged cap-receiving portion of uniform thickness at, and for some length from both sides of, the discharge-opening, with respect to the direction of movement of the cap. The total length of such thicker portion is about the same as the length of the cap. In the uncovering position of the cap at the other end of the cap-seat, the flanges 22 are thinner transversely. The short transition from the thinner to the thicker portions of the flanges 22, at the middle thereof, is not abrupt but is smooth and gradual.

The enlarged or thicker portions may be provided on the flanges 22 by shaping the top contour of the cap-seat as shown in Fig. III, so that the tops of the channels 24, which are defined by the lower or under sides of the flanges 22, are straight and the top of the cross member 20 depressed along the open position of the cap; or the bottom sides of the flanges 22 may be shaped to provide the thicker portions, as shown in Fig. VI, thereby leaving a smooth flat top surface on the cross member 20 for the cap to slide on.

The cap-seat 6 comprises a first surface 37, within which the discharge-opening 8 terminates, and a second surface 38. The bottom horizontal part of the edge of the flange 22, that is occupied by the cap 26 in its fully closing position, is parallel to the surface 37 which is at least the length of the cap. The cap-bridging member 30 has a bottom surface 39 which has the same shape as the first surface 37 of the cap-seat 6. In fully closing position of the cap, the surfaces 37 and 39 are evenly pressed together, around the discharge-opening 8. In partially closing position of the cap, the portions of the surfaces 37 and 39 which are in contact also are evenly pressed together. The second surface 38 is a vertical distance from the bottom edge of the flange 22, which is less than that between this edge and the surface 37 so that the cap, in open position, is loosely confined to the cap-seat.

In the embodiments shown in Figs I-VII, the thicker portion of each flange 22 and the associated cap-channel are dimensioned so that the former fits snugly in the latter in any closing position of the cap, and in such positions the bottom surface 39 of the bridging member 30 presses against the part of the surface 37 which it contacts, with a uniform pressure, the pressing forces acting in planes which are normal to the direction in which the cap is moved to such closing position. For convenience I designate the aforesaid surfaces 37 and 39 as pressure-surfaces. In these embodiments, the width of the cap-seat pressure-surface 37 comprises the horizontal width of the leg 18 plus twice the horizontal width

of a flange 22. Generally, the thickness of the thicker portions of the flanges 22 should be the same as the vertical width of the cap-channels. Preferably, the cap side-walls 28 should be comparatively thin, with elasticity and resiliency, and the bridging member 30 relatively thick and stiff so as to prevent it from bowing.

When the cap-seat is depressed in the opening position of the cap, as shown in Fig. III, less material is required for the cap-seat as compared to the material required for a cap-seat having a flat top as shown in Fig. VI. The pressure-surfaces 37 and 39 of the cap and cap-seat need not necessarily include the top of the cap-seat flanges, but may, if desired, be above it. Such an embodiment is shown in Figs. VIII-X in which the top pressure-surface 37' of the cap-seat is above, and discontinuous with respect to, the cap-seat flanges 22'. In this embodiment, in any closing position of the cap 26', the abutting parts of the flanges 22' and 32', which are in contact at the joints 41', cause that part of the bridging member 30' which is on the pressure-surface 37' to press thereon. This action arises because the horizontal bottom part of each cap-seat flange 22', which extends along the closing position, is spaced a distance below the pressure-surface 37', which is substantially the same as the distance between the horizontal top of the cap-flange 32' and its bridging member 30'. The surface 38' and the cap pressure-surface 39' are not forcibly pressed together in any position of the cap.

In the preferred embodiment, the bridging member of the cap comprises a deformable seal consisting of a compressible material 40, such as cork, and an outer protective foil 42 of thin metal, such as aluminum foil; such seals being common. The bottom of the bridging member is provided with a shallow seat into which the cork and foil are fitted and retained so as not to be displaced during movement of the cap. In Fig. II such a seat is shown as formed in the bridging member 30 by two lengthwise retaining projections 43. The foil may project slightly beyond these projections in opening position of the cap, being forced upwardly when the cap is moved to closing position, the cork being compressed and insuring a tight mating fit between the pressure-surfaces of the cap and cap-seat.

In the embodiment shown in Fig. I the pressure-surfaces of the cap and cap-seat, in closed position of the cap, extend from both sides of the discharge-opening for relatively significant distances so that the discharge-opening can be tightly closed without requiring the use of excessive or inordinate manual force to move the cap.

In opening position, the cap is fairly loose on the cap-seat. When the cap is moved toward its closing position, the gradual increase in the thickness of the flanges 22 insures proper engagement of the cap side-wall channels with the thicker portions of the flanges 22 and the ready sliding of the cap to closing position with the pressure between the cap and cap-seat gradually increased as the cap initially moves into engagement with the thicker portions of the flanges, that is, into closing position.

Preferably the total pressure-force between the cap and cap-seat, produced by sliding the cap on the thicker portions of the flanges 22 or 22', should not be so great as to make manual sliding motion of the cap too difficult, but should be sufficient to cause the cap to remain in closed

position or in a partially closing position where an edge of the cap cuts across the outlet end of the discharge-opening 8.

Because the pressure between the coating pressure-surfaces of the cap and cap-seat is substantially normal, that is, perpendicular, to the general direction of movement of the cap, the frictional characteristics of the cap and cap-seat can frequently be ignored, the cap remaining in whatever closing position it is placed because there is no component of force tending to displace it from such position. This is an especially important advantage when my novel closure means has a cap-seat of glass applied to a glass container or top-wall.

In glass receptacles, such as the flask 4 of Fig. VII, provided with the closure means of my invention, it is frequently advantageous to locate the glass cap-seat very near or substantially at an edge of the top-wall 12, and the discharge-opening nearer the end of the cap-seat, which is toward such edge so that the liquid contents of the receptacle will pour easily. The cap 26 for such cap-seat is provided with side-walls 28 which can resiliently spread so that the cap can be snapped or otherwise forced downwardly over the body-portion of the cap-seat. This permits the cap-seat with all its end stops to be integrally formed in the making of the receptacle. To facilitate placing the cap on the cap-seat the in-turned lugs or flanges 32' of the cap 26' are provided with inner edges 44 which are curved relatively upwardly and inwardly so as to slide readily over the top cross member 20' and gradually spread the cap side-walls 28' apart until the in-turned flanges 32' pass below the cap-seat flanges 22' whereupon the side-walls 28' of the cap will spring into a position where the flanges 32' interlock with the flanges 22'; the flanges 32' having flat upper surfaces for sliding along the flat lower surfaces of the flanges 22'. A suitable one-piece resilient cap may be made from any number of present-day "plastics," or otherwise suitably formed.

I have shown the top surface 37 of the cap-seat in the embodiments described in Figs. I-VII, as flat and smooth, the cooperating under surface 39 of the cap being of the same general shape so as to fit it; but it is obvious that these surfaces may be otherwise fitted or formed. For example, the cap-seat surface may be made convex instead of flat and the cap surface concave to correspond, as shown in Figs. VIII-X.

In the drawing, the receptacles have been shown upright, but the top surfaces of the cap-seats and the bottom sides of the cap-seat flanges are respectively outer surfaces and inner surfaces, with respect to the body-portions of the receptacles in which the contents can be stored.

While I have described my invention in forms which I now prefer and applied to selected types of receptacles, it is obvious that my invention has broader application and may be constructed in different equivalent manners.

The invention herein described and claimed comprises the invention described and claimed in my copending application, Serial No. 370,590, filed December 18, 1940, which is hereby superseded, that the instant application be a continuation-in-part.

I claim:

1. A closure means for a receptacle, comprising an extended cap-seat having a discharge-opening passing therethrough, said cap-seat having sides and a cap-receiving top provided with

a pressure surface around said discharge-opening; a cap restrictably slidable along said cap-seat to an open position uncovering said discharge-opening and to positions respectively fully and partially closing said discharge-opening; said top pressure surface extending for some length from said discharge-opening smoothly in the direction-lines in which the cap can be moved; said cap comprising spaced side-walls and a bridging member having a bottom pressure surface which fits said top pressure surface; said cap-seat sides and cap side-walls being provided with cooperating two-part means for interlocking the cap and the cap-seat, said cooperating means comprising flange means on one of said parts and means on the other of said parts cooperating with said flange means for causing said bottom pressure surface of said bridging member to be abutting and matingly pressed against said top pressure surface with a substantially even pressure, when in closing position, and for causing it to be substantially free from pressure, when in open position, said cooperating means comprising a transition portion for causing smooth coaction of said parts as the cap is moved between said closing and open positions.

2. A closure means for a receptacle, comprising an extended cap-seat having a discharge-opening passing therethrough, said cap-seat having sides and a cap-receiving top provided with a pressure surface around said discharge-opening; a cap confinably slidable along said cap-seat for controlling said discharge-opening; said top pressure surface extending for some length from said discharge-opening smoothly in the direction-lines in which the cap can be moved therealong; said cap comprising spaced side-wall means and a bridging member which fits said top pressure surface; said cap-seat sides being provided with flange means having a first portion of substantially uniform thickness along fully closing position for the cap, and a portion of lesser thickness along the open position for the cap; said cap side-wall means being provided with channel means; said first portion of said flange means being of thickness to snugly fit said channel means; the bottom of said first portion of said flange means being substantially parallel to the said top pressure surface, said flange means having a gradual transition portion between its said first portion and its second-mentioned portion.

3. A closure means for a receptacle, comprising an extended cap-seat having a discharge-opening passing therethrough, said cap-seat having sides and a cap-receiving top provided with a smooth pressure surface around said discharge-opening; a cap confinably slidable along said cap-seat for controlling said discharge-opening, said cap comprising spaced side-wall means and a bridging member having a bottom pressure surface between said side-wall means, said side-wall means being provided with inwardly directed flange means having an upper sliding edge at a predetermined distance from said bottom pressure surface; said cap-seat sides having outwardly directed flange means having a lower edge with a part along the cap-seat pressure surface for engaging said upper sliding edge, said part of said lower edge being a distance from

said cap-seat pressure surface which is at least said predetermined distance; said part of said lower edge, said upper sliding edge and said pressure surfaces being substantially parallel when the cap is in closing position; said pressure surfaces being of substantially the same shape whereby they will mate when pressed together; said lower edge having a second part which is a distance from the top of said cap-seat, that is less than said predetermined distance.

4. The closure means of claim 3 in which said lower edge of said cap-seat flange means is substantially straight for substantially its entire length.

5. The closure means of claim 3 in which the said cap-seat flange means comprises a smoothly sloped portion intermediate fully closing and open positions for the cap.

6. As an article of manufacture, a glass receptacle comprising an outer wall provided with an opening, an integral outer body-portion extending from said wall near an edge thereof, said body-portion having a smooth top surface comprising a first and second portion, said opening passing through said body-portion and terminating at said first portion of said top surface, said body-portion having flange means spaced from said wall for providing a channel means for interlocking a cap slidable along said body-portion between closing position for said opening along said first portion of said top surface and an opening position along said second portion of said top surface, said flange means having a lower edge with a part which is substantially parallel to said first portion of said top surface, said lower edge having another part which is spaced from said second portion of said top-surface a distance that is less than the distance between the first said part of said lower edge and the said first portion of said top surface, said flange means being formed to provide a smooth transition portion between said parts of said lower edge.

7. A receptacle having a closure means comprising a cap-seat provided with a discharge-opening, said cap-seat having a flange along which a cap can be slid between open and closed positions for controlling said discharge-opening, said flange having a portion of uniform thickness for maintaining even pressure between the cap and cap-seat, when in closed or partially closed position, in combination with a portion of lesser thickness and a smooth transition portion between them.

8. A receptacle having a closure means comprising a cap-seat provided with a discharge-opening, said cap-seat having an outer surface and a flange along which a cap can be slid to occupy open position, partially closing position or fully closing position for controlling said discharge-opening, said flange having a portion with an inner surface in spaced parallel relation to the part of said outer surface, which includes the end of the discharge-opening, for maintaining even pressure between the cap-seat and the cap in partially closing and fully closing positions, in combination with another portion having an inner surface spaced a lesser distance from the outer surface, and a transition portion between said flange portions.

SIDNEY J. RUDOLPH.
